UNITED STATES PATENT OFFICE.

KEEFFE S. O'KEEFFE, OF SAN FRANCISCO, CALIFORNIA.

MANUFACTURE OF BRUSHES.

SPECIFICATION forming part of Letters Patent No. 551,994, dated December 24, 1895.

Application filed December 31, 1894. Serial No. 533,463. (No model.)

To all whom it may concern:

Be it known that I, KEEFFE S. O'KEEFFE, a citizen of the United States, residing at San Francisco, in the county of San Francisco and 5 State of California, have invented certain new and useful Improvements in the Manufacture of Brushes; and I do hereby declare that the following is a full, clear, and exact description thereof.

My invention relates to improvements in the manufacture of brushes, and my object is to do away with the commonly-used wooden head or stock to which the bristles are secured and to replace it with an indestructible metallic stock of peculiar construction provided with means for firmly securing the bristles. Nearly all kinds of brushes are intended to be used with water for different purposes, and after a short period of use the water causes 20 a wooden stock to split, crack, and warp. In addition to this disadvantage the wooden stock soon becomes so thoroughly water-soaked that it causes the bristles or fiber to rot and drop out, thus speedily destroying its 25 usefulness.

By doing away with the wooden stock and using instead one of metal I can not only make a cheaper, lighter, and stronger brush, but a more attractive and presentable article. At 30 the same time I entirely obviate the objections above stated to the wooden stock, since the metallic stock will neither split nor warp, nor will it retain moisture long enough to injure the material of which the brush part is 35 composed.

My invention can be employed in the manufacture of all kinds of brushes, and I may mention in illustration hair and other toilet brushes, scrubbing-brushes, shoe and hat 40 brushes, stable-brushes, paint-brushes, and so on.

In the accompanying drawings I have shown different styles of brushes for different purposes, all, however, constructed according to 45 my invention.

Figure 1 is a side elevation of a scrubbing-brush partly broken away to show a longitudinal vertical section. Fig. 2 is a similar view of a flesh-brush. Fig. 3 is a broken plan 50 to illustrate the relative positions of the perforated plates forming the brush-stock. Fig. 4 is an end view, partly in cross-section, of the

brush shown in Fig. 2. Fig. 5 is a bottom plan to show a special construction for hair-brushes. Fig. 6 is a broken plan of a stock 55 for a round brush, such as a paint-brush.

I construct the stocks of my brushes from two or more perforated plates of metal or other material, which will be light, cheap, and practically indestructible. Hard - rubber 60 sheets might be used, or bone, or even wood for some kinds of brushes. I prefer to use three of such plates A, B, and C. Supposing them to be made of metal, they can be stamped out with dies and perforated at one 65 operation. Into these perforations a b c, which are caused to register, are drawn or threaded the bristles, fiber, wires or other material which form the brush. As shown in Fig. 1, which shows a scrubbing-brush, the 70 tufts of bristles are inserted in the shape of a staple. In making a reversible brush, Fig. 2, the brush material is threaded entirely through the registering-perforations.

Whatever the construction of the brush 75 may be or for whatever purpose intended, the middle plate of the series is used as a locking-plate for securing and holding the bristles firmly and rigidly in position. This result is produced by moving such plate longitudinally, Figs. 1 and 2, independently of the other plates of the series, so as to cramp the bunch or tuft of bristles between non-registering perforations, as clearly illustrated. This being done all the plates are secured together 80 by rivets, as shown at d in all the figures. The perforations in the locking-plate are preferably made somewhat elongated or with a pointed end, Fig. 3, so as to clamp the bristles to better advantage. In the case of a paint- 85 brush, the stock of which is shown in Fig. 6, this locking or cramping effect is produced by giving the circular plate B a partial turn independently of the plates A and C, and then riveting all the plates firmly together. 90

Light plates of aluminum or any other metal being very easily and cheaply worked into different shapes and forms, I can give any desired conformation to my brushes at very little expense. Thus in the case of the scrubbing-brush, Fig. 1, in which it is desired to incline the bristles at the ends, the plates composing the stock can be stamped out with the ends inclined, as shown, so that the bristles 100

when inserted will naturally assume their correct position. This saves all the labor and expense of boring at an angle into a wooden stock, as must now be done. Similarly in the case of the flesh-brush, Figs. 2 and 4, the plates are formed in concavo-convex end elevations, and, the bristles being drawn entirely through the stock, will be crowded on the concave side, making a short stiff brush, while on the convex side they will be spread, making a longer and softer brush.

Single brushes like Fig. 1 will preferably have the staple-shaped ends of the bunches of bristles concealed by a layer or coating *e* of wax or other substance, and may, if desired, be provided with a wooden false back *f*, as shown, in order to give a neat finish.

The hair-brush shown in Fig. 5 is constructed like the other brushes shown, with the exception that a series of triple plates are used to form the stock. These plates are more properly perforated strips imposed upon each other, as before described. Each middle strip forms, as before, a locking-plate for the bristles inserted into the perforations, and the idea of so constructing this particular brush is to render it easy to clean. In ordinary use the whole series of strips is held within a frame *D*, of wood, metal, rubber, or any suitable substance, from which they can be removed. In the drawings they are shown as held by transverse rods *g* passing through the frame, the strips being riveted together.

When removed from the frame, the separate parts of the stock, each forming only a small part of the brush, can be separately washed, and being preferably made of non-oxidizable metal will not rust or tarnish, but will dry quickly. This advantage of having easy access to every part of a hair-brush, so as to quickly and thoroughly clean it, will be

appreciated by all users of such brushes as now constructed.

It will be understood that the brushes shown in the drawings are merely illustrative of certain kinds selected from the great variety of brushes for different purposes, in all of which my invention is capable of embodiment.

What I claim is—

1. In a brush and in combination, a head or stock composed of flat plates having perforations and secured together with their surfaces in the same plane, one of such plates being a locking plate and having its perforations out of direct line with those in an adjoining plate, and bristles cramped and held within said perforations, substantially as described.

2. In a brush, a head or stock composed of a plurality of separate groups of perforated plates or strips, each group being composed of two or more of such strips, one of which strips is a locking strip having its perforations out of direct line with those in an adjoining strip, and separate bunches of bristles cramped and held in said perforations, the said groups being arranged side by side and parallel to one another and held together, substantially as described.

3. In a brush the combination with a frame and handle, of perforated metal strips arranged in parallel groups of three each, and removably secured to said frame, and bristles secured in and by said perforated strips, substantially as described.

In testimony whereof I have affixed my signature, in presence of two witnesses, this 28th day of December, 1894.

KEEFFE S. O'KEEFFE.
